APPARATUS FOR TOASTING BREAD, ETC.

Maurice H. Graham, St. Louis Park, Minn.

Application November 13, 1931, Serial No. 574,694

9 Claims. (Cl. 219—19)

Broadly considered, this invention relates to an improved process of and apparatus for cooking substances adapted to absorb and contain a varying amount of moisture; but particularly, the invention is directed to a process and apparatus for toasting bread and baking waffles. The term "cooking" is herein used in a broad sense to include the various different kinds of cooking operations, such as the above noted toasting and baking actions, and others which essentially decrease the moisture content or percentage of moisture contained in the article subjected to heat.

Generally stated, the invention consists of the novel operations, co-ordination of operations, devices, combinations of devices and arrangement of parts hereinafter described and defined in the claims.

In the toasting of bread and baking of waffles, there has hitherto been provided various different kinds of apparatus equipped with "timed" means for rendering the heat radiators (usually electrical heating elements) inactive on the substance being cooked. Such timed apparatus operates according to predetermined setting of clock mechanism or the like to render the heat inactive on the substance being cooked at the termination of a definite interval of time and regardless of the condition or the extent to which the substance has been toasted, baked or otherwise cooked. In the toasting of bread, for example, the apparatus when once set, would act on a piece of bread as long as it would upon a damp or moist piece of bread, and if any account was taken of the different lengths of time required to properly toast the bread, the time interval would have to be estimated and the timing mechanism reset so as to approach as nearly as possible the toasting operation desired. Such operations are not only inconvenient but never accurate nor certain of accomplishing the desired result.

In the use of these "timed" toasters, different operations have been utilized to render the cooking or toasting operation inactive on the toast, to wit: (a) by cutting off the current supply to the electrical heating elements or radiators (b) by moving the toast out of the zone of action of the electrical heating elements or radiators; (c) by moving the electrical heating elements or radiators away from the toast; and (d) by combining two or more of the above noted actions, a, b, and c.

My invention makes a radical departure from the above noted older method and apparatus for

controlling toasting of bread, baking of waffles and other analogous cooking actions, in that it takes advantage of the fact that the amount of moisture contained in bread, waffle dough (or other substances that are adapted to absorb and contain a varying amount of moisture), will vary during the toasting, baking or other cooking operation, and that there will be a corresponding variation in the electrical conductivity in the substance; and that by using an electric circuit, arranged to include a part of the substance being cooked, and in said circuit, a device that is responsive to varying current flow, (herein designated as a current-measuring device), substantially the exact condition to which the substance has been toasted, baked or otherwise cooked may be determined and the cooking action terminated. The term "current-measuring device" is used in the sense that the said device is sensitive to and/or determines when the current has reached a certain flow.

In experiments carried out to date, I have found that the best results can be obtained by an arrangement wherein the cooking action is terminated when the current flow in the circuit is decreased to a predetermined extent by the increased resistance in the circuit, due to the decreasing moisture content in the material being cooked or in a portion thereof. I further found, that the best results can be obtained by dividing the electrical controlling circuit by means such as electrodes insertable into the bread or material being cooked, in such manner that the current will flow through only a small interior portion of the bread or substance, thereby utilizing only an inner portion of the bread or material as the variable resistance controlling factor, and rendering the control less affected by the heating means from the cooking than is the case when the electrodes have contact only with the external surface of the bread or substance being cooked.

Obviously, under this improved process and by the improved apparatus, the length of time of the cooking operation will depend, not on any predetermined definite interval of time, but upon the extent of time, under the heat applied to the substance, required to cook the substance to a predetermined desired condition. In the toasting of a relatively dry piece of bread, for example, the heat will be applied to the bread for a shorter interval of time than it will to a relatively moist piece of bread, but the resulting toast in both instances will be toasted to a pre-

determined condition, the condition being the same in both instances.

The scope of utility of the generic features of the invention has been generally indicated. The invention in the instant case is, however, particularly directed to an improved automatic toaster and, as designed for this purpose, the apparatus includes various highly important novel features, which especially adapt the apparatus for the purpose of toasting bread, but some of which features will be found useful in connection with waffle bakers and the like.

In the accompanying drawings which illustrate the invention especially designed for the toasting of bread, like characters indicate like parts throughout the several views.

Referring to the drawings:

Fig. 1 is a horizontal section taken through the complete toaster on the line 1—1 of Fig. 2;

Fig. 2 is a front to rear vertical section taken through the toaster on the line 2—2 of Fig. 1;

Fig. 3 is a transverse vertical section taken through the toaster on the line 3—3 of Fig. 2;

Fig. 4 is a transverse vertical section taken through the toaster on the line 4—4 of Fig. 2;

Fig. 5 is a transverse vertical section taken through the toaster on the line 5—5 of Fig. 2;

Fig. 6 is a fragmentary perspective showing a part of the casing and particularly illustrating the latch trip and trip-actuating mechanism;

Fig. 7 is a fragmentary detail taken in horizontal section approximately on the line 7—7 of Fig. 6;

Fig. 8 is a diagrammatic view illustrating the electric circuits of the improved toaster;

Fig. 9 is a view corresponding to Fig. 3, but illustrating a modified construction;

Fig. 10 is a vertical front to rear section taken on the line 10—10 of Fig. 9, some parts being broken away and some parts being removed;

Fig. 11 is a view corresponding to Fig. 4 but illustrating a modification of some of the elements;

Fig. 12 is a view corresponding to Fig. 3, but illustrating a modification of some of the elements;

Fig. 13 is a fragmentary vertical section taken approximately on the line 13—13 of Fig. 11;

Fig. 14 is a view corresponding to Figs. 3 and 12 but illustrating a still further modification of some of the elements;

Fig. 15 is a detail with parts broken away chiefly in section but with some parts shown in full, showing in detail an arrangement of the controlling electrodes as a single barb; and

Fig. 16 is a diagrammatic view illustrating a modified form of the apparatus in which an increased current flow is utilized to control the toasting of bread.

The toaster illustrated in Figs. 1 to 8, inclusive, will first be described. The rectangular outer shell or casing 11 of the toaster is preferably a thin sheet metal structure mounted on a sheet metal or other suitable base 12 and provided in its top with a large rectangular opening 13 through which the bread slice y may be inserted into the toaster and through which the toast may be ejected therefrom.

Mounted within the casing 11, but spaced from the side walls thereof and secured on the base 12 is a rectangular inner shell preferably of sheet metal and which affords an oven 14 into which the bread to be toasted is inserted through the opening 13. Suitably mounted within the oven 14 adjacent but spaced from the side walls there-

of are electrical heating elements or heat radiators 15.

Secured to the top of the oven and depending therefrom on each side of the opening 13 are ejector guide rods 16 and mounted to slide vertically on these guide rods is a bread carrier or toast-ejector 17 which, as shown, is of skeleton form and comprises a plurality of short cross bars secured to a common rod 17a. The ejector rod 17a at one end, to wit: as shown, at its front end, is rigidly secured to and supported in a horizontal position by a carrying head 18 mounted and guided for vertical movements and, as shown, this carrier head 18 is in the form of an upright flat bar having laterally projecting lugs mounted to slide on an ejector guide post or rod 19 secured at its lower end to the base 12 and at its upper end to the top of the casing. Preferably, the head-forming bar 18 is provided with anti-friction rollers 20, see Figs. 2, 5, and 6, that engage the post 19. On one side, head bar 18 is provided with a projecting latch lug 21 bevelled on its under side.

For co-operation with the latch lug 21 to hold the ejector down when depressed, there is provided an ejector latch in the form of a spring-pressed latch bolt 22, see particularly Figs. 5 and 6, that automatically engages over said lug 21 when the ejector is pressed downward. This latch bolt 22 is shown as mounted in a small two-pronged bracket 23, which in turn is secured to a larger bracket 24 rigidly applied to one side of the casing 11. These parts just described and certain other co-operating parts are mounted in the space between the casing and the oven, preferably at the front portion thereof. The outer end of latch bolt 22 is connected to the depending arm of a latch trip shown as in the form of a small bell-crank 25, pivoted to a lug on the bracket 24. For manual release, this bell-crank 25 is shown as provided with a trip arm 26 that projects outward through a slot 27 in one side of the casing 11, as best shown in Figs. 5 and 6.

For setting the ejector in a depressed position and for starting the toasting action, there is provided a master lever 28, shown as pivoted to lugs on the rear wall of the casing 11 and extended along one side of the casing and out through an opening in the front end of the casing where its free end may be readily engaged and depressed. This lever 28 has a depending arm 29 that is connected by a link 30 to the depending arm of a bell-crank 31 pivoted to the base 12. Arm 31 is connected to one end of a quite strong tension spring 32, the front end of which is anchored to the base 12. The upper arm of the bell-crank 31 has a wide end shown as covered with an insulating material 33 such as vulcanized wood fiber, best shown in Figs. 2 and 3. This bell-crank, as will presently be noted, acts as an electrode projector.

The electrodes just referred to in the form illustrated in Figs. 1 to 8, inclusive, are in the form of small sharp pointed pins 34 mounted in supporting blocks 35 insulated from but secured to the depending free ends of light spring-acting hanger bars 35a, the upper ends of which are secured to the top of the oven 14, one just inside of each heating element or radiator 15. At their lower ends, electrodes 34 are provided with heads 36 that are arranged to be engaged and pressed upward by the insulated face 33 of bell-crank 31. Springs 37 interposed between the blocks 35 and heads 36 normally hold the electrodes pressed downward as far as permitted by small collars 75

38 provided on said electrodes. The blocks 35 have upwardly extended gauge plates or portions 39, the upper edges of which are beveled, so that the slice of bread y will readily slide between the same. These gauge plates determine the distance from the disposed faces of the bread at which the electrodes 34 will penetrate the bread. It should be noted that as a convenient way of connecting the master lever 28 to the head 18 of the ejector 17, said lever is formed with a laterally offset free end equipped with the projecting stud or finger 28^a that engages through an ear 18^a of said head bar, as best shown in Figs. 1, 5, and 6.

15 Carried by the ejector 17 and projecting upward from opposite sides thereof are bread grippers preferably in the form of leaf-like spring arms 40, the free upper ends of which are arranged to frictionally clamp the opposite faces of the bread slice and to perform important functions hereinafter described. In the particular arrangement described, the gripper arms 40 are provided with cam lugs 41 which, when the ejector 17 is moved downward to a certain point hereinafter more particularly noted, will be engaged by cam flanges 42 of upright strips 43 that are rigidly secured at their lower ends to the base 12 and at their upper ends to the top of the oven. It should be here further stated that when cam lugs 41 are engaged with the fixed cam flanges 42, the ends of the gripper arms 40 will be pressed against and caused to quite firmly hold the bread slice against upward slipping movement under downward movement of the ejector to set position.

As best shown in diagram view Fig. 8, the electrical heating elements 15 are in a supply circuit 44 in which is interposed a normally open electric switch in the form of a circuit maker and breaker including fixed contacts 45 and a movable contact 46. As a convenient way of supplying circuit to the control circuit which includes the electrodes 34 and will include the slice of bread when the latter is positioned for toasting, the said electrodes are arranged in a shunt 47 that is connected across the leaves of the main or supply circuit 44. A small and sensitive electro-magnet 48 is interposed in one of the leads of the shunt 47 and is arranged to act upon an element that carries the movable switch contact 46.

The movable contact 46 of the control or master switch (made up of the above noted contacts 45 and 46) is carried by a trip actuator that is subject to the action of the electro-magnet 48. The trip actuator shown is in the form of a quite heavy type armature 49, to which the contact 46 is secured but from which it is electrically insulated, see particularly Figs. 5, 6, 7, and 8. The electro-magnet 48 is supported by a bracket-line projection of a regulating lever 51, the free end of which projects through a slot 52 in the front of one side of the casing 11 and as shown, co-operates with graduation marks on the said casing. A rod or long stud 50 pivotally connects the armature 49 to the lever 51 and said lever to the bracket 24. By reference to Fig. 6, it will be noted that the free upper portion of the armature 49 stands in a position so that when dropped, it will strike the upper arm of latch-tripping bell-crank 25, depress the same and retract the latch bolt 22. Lever 51 will be held against extended movement in whatever position it may be set, but may be adjusted to set the armature 49 in a more or less

inclined position in respect to perpendicular and this for a purpose which will appear in the description of the operation.

As will fully appear in the description of the operation, the armature 49 which can move upward far enough to engage contact 46 with contacts 45, will be held in that circuit-closing position by armature 49, if at that time there is sufficient current through shunt circuit 47 to cause said magnet to hold said armature against the action of gravity; and hence, as a further important feature, there is provided a trip actuator re-setting device, which when the ejector with the bread slice thereon is forced down to its extreme position and set for action, will move the armature 49 to the circuit-closing position just stated.

This re-setting device in the particular arrangement illustrated, comprises a small vertical re-set rod 52^a, see Fig. 6, guided for vertical movement through a lug 53 on bracket 24, and at its lower end pivotally but adjustably connected to the long end of a small re-set lever 54 pivoted to a lug 55, on the base 12. The short end of this lever 54 stands in a position to be engaged by the lower end of ejector head bar 18 when the ejector is pressed to its extreme lowermost position. Here attention is called to the fact that when said bar 18 is pressed down to its extreme position, upper end of rod 52^a will engage trip-acting armature 49 and move the same to the circuit-closing position stated. Here, however, it is important to note that when head bar 18 is pressed down to its extreme lowermost position, as just stated, latch lug 21 on said bar 18 will be considerably below the co-operating end of latch bolt 22, so that when pressure is removed from the projecting end of master lever 28, spring 32 will act to impart a slight initial upward movement to ejector and bar 18 sufficient to carry the upper end of rod 52^a below the upper arm of trip bell-crank 25, before lug 21 has engaged latch bolt 22.

Operation

The operation of the device illustrated in Figs. 1 to 8, inclusive, quite briefly summarized is as follows: Normally, that is, when the toaster is empty and idle, the master lever 28 will be in its uppermost position, under tension from spring 32; the ejector 17 will be in its raised or uppermost position; the latch trip-actuating armature 49 will be dropped onto the upper arm of trip lever 25; the pointed electrodes 34 will be dropped down below the upper surface of the ejector 17; and the trip switch 45—46 will then be open so that the current to the heating elements or radiators 15 will be cut off and magnet 48 will be de-energized. Also in the normal or raised position of the ejector 17, the bread grapples or gripping fingers 40 will be carried to positions in which their cam lugs 41 will be above the cam flanges 42 and at such time, the two fingers 40 will be sprung apart far enough to permit ready insertion of the bread slice y between the same and onto the ejector 17.

When a slice of bread is to be toasted, it will, of course, be inserted through the opening 13 in the top of the casing, and placed upon the then raised ejector 17 between the gripping fingers. The only operation that needs to be performed by the operator to start the toaster into action is to press the master lever as far as it will go. The operations that take place when lever 28 is forced down to its lowest position as just stated are as follows:

The ejector 17, of course, commences its down- 75

ward movement simultaneously with the downward movement of lever 28 and continues such movement to its extreme lowermost position. Under the downward movement of the ejector, 5 but before any of the other operations hereinafter noted have taken place, the cam flanges 42 acting on the yielding grippers 40 press the same against the bread slice y, causing the same to grip and hold the bread with sufficient friction to prevent 10 lifting of the bread from the ejector when a little later on the pointed electrodes 34 are forced in the bread. A little further downward movement of the ejector 17 after the bread grippers 40 have been closed against the bread slice, forces 15 the lower portion of the bread slice between the gauge plates 39, thereby positioning the electrodes 34 to pierce the bread close to its exposed outer surface. Under still a little further downward movement of the ejector 17, bell-crank 31, acting 20 on the lower end heads of electrodes 34, force the pointed upper ends of the electrodes upward and above the ejector 17 and through the bread, substantially as shown in Fig. 3. This engagement 25 of the electrodes with the bread closes the circuit through the bread at that point with a resistance that will be greater or less, depending on the amount of moisture in the bread, but which, with the kind of bread used for toast, regardless of the amount of moisture therein, will have an 30 electrical conductivity sufficient to permit a flow of electricity through the magnet 48, when an instant later the switch 45-46 is closed.

The final and extreme part of the downward movement of ejector 17 causes the lower end of its head bar 18 to engage the short end of re-set lever 54, thereby moving rod 52^a upward and causing the latter to lift the armature 49 far enough to close switch 45-46; and instantly, upon thus closing of switch 45-46 magnet 48 becomes energized and acting on armature 49, will hold said switch closed and maintain the proper toasting current through the electrical heating elements 15 until a time presently to be noted. Upon release of lever 48 from its extreme lower 45 position, ejector 17 makes a slight upward movement until lug 21 engages latch 22 by which latter further upward or return movement, under the tension of spring 32, is interrupted by said latch; but this movement, as already noted, permits rod 52^a to drop below the upper arm of trip bell-crank 25 so that it will not interfere with the tripping action of the armature presently to be noted.

When the switch 45-46 is closed and the 55 ejector latch is down in its lower portion, as above stated, the current from the main circuit will flow through the electrical heating elements and continue the toasting action of the bread until by the evaporation of moisture incident to the toasting action, the current flow through the bread between electrodes 34 is so decreased by the increasing resistance in the bread that the amount of current permitted to flow through the shunt 47 will not keep magnet 48 energized with sufficient 60 force to hold armature 49 from dropping under the action of gravity and thereby opening switch 45-46. When this weakening of the current, through magnet 48 to the extent that armature 49 is released, takes place, said armature will drop by gravity against the upper arm of bell-crank 25, thereby retracting latch bolt 22 and permitting the ejector 17 and lever 28 to be quickly thrown to uppermost position under the action of spring 70 32. Initial movement of armature 49 from its raised position, of course, opens switch 45-46 and

immediately cuts off current flow through the electrical heating elements or radiators 15.

From the above it is evident that, as already stated, in the introduction of the specification, the length of time that the bread will be subjected to a toasting action is not definite or predetermined by the setting of the device, but will be dependent on the amount of moisture in the bread that completes the circuit between the electrodes 34. Provision, however, is made for 10 varying the extent of dryness in the toast required to cause the electro-magnet 48 to release the latch trip actuator, to wit: the armature 49 so that by setting of lever 51, the apparatus may be arranged to produce lightly cooked or very 15 crisp toast. With the particular device illustrated, the above adjustment is accomplished by tilting the lever 51 so as to set armature 49 at various different angles in respect to a vertical when in circuit-closing position and subject to 20 electro-magnet 48. It is evident that if armature 49 be set near a vertical position, gravity will exert a much less force tending to drop said armature, than it will if said armature be set at a greater angle to a vertical than in a 25 horizontal position. Otherwise stated, the further down lever 51 is turned and the more nearly approaching a horizontal armature 49 is set, the lighter will be the toasting action, and conversely, the more nearly vertical positions said 30 lever and armature are set, more crisp will be the toasting action.

When latch 22 is retracted and the ejector 17 by spring 32 is quickly thrown upward to its normal position, the toast will be well projected 35 out through the opening 13 so that it can be engaged by the fingers and lifted out of the toaster. Obviously, by depression of lever 28, the ejector 17 should be thrown down to its lowest position, when no bread slice is in the toaster to complete 40 the shunt circuit 47, latch 22 will operate and armature 49 will be moved upward to close switch 45-46 just as would be the case if a slice of bread were placed in the toaster; but in this case, shunt circuit will not be closed and the 45 magnet 48 will not be energized and hence, when pressure is released from lever 28 so as to permit head bar 18 to move its lug 21 up against latch 22, armature 49 will be released and will drop onto trip lever 25, causing latch 22 to be 50 released and the mechanism restored to normal position in the same manner as when the toasting operation has been completed. If at any time it should be desirable to trip the ejector, cut off the current and restore the parts to normal 55 positions, in the midst of or before the completion of a toasting operation, all that is necessary to accomplish that result would be to press upward on the projecting arm 28 of bell-crank 25, thereby releasing the latch 22.

In the modification illustrated in Figs. 9 and 10, the parts may be assumed to be substantially as heretofore described, except that the electrodes 56 for the shunt circuit are arranged to contact with the sides of the bread slice y 65 and are carried by the upper ends of levers 57 intermediately pivoted at 58 to an insulating section 12^a of base 12, and the lower ends of these levers 57 are connected to coiled spring 59 to the base 12. The springs 59, as shown, are made 70 up of coiled sections connected by links 60 of insulating material. The rollers 57^a on ejector 17 operate on offset intermediate portions of levers 57 to move the electrodes 56 into contact with the bread when the latter is lowered in position 75

for toasting and move said electrodes out of contact with the bread while the bread is being moved to and from toasting position.

With the arrangement of electrodes shown in Fig. 9, the controlling current is caused to pass completely through from one side to the other of the bread.

The construction illustrated in Figs. 11, 12, and 13 is like that illustrated in Figs. 1 to 8, inclusive, with the following exceptions: The electrodes or pins 34' that correspond to the earlier described electrodes or pins 34 are rigidly secured to the heads 35' that correspond to the earlier described heads 35; and the gripper arms 46 are provided with teeth 40' that get a positive grip on the bread slice y, which will positively pull the bread slice down onto the pins or electrodes 34'. Otherwise stated, in the construction illustrated in Figs. 1 to 8, inclusive, the electrodes or pins were movable and were forced upward into the bread slice while in this latter described construction, the pins are relatively stationary and the bread slice is moved downward to cause the electrodes to penetrate the bread.

The construction illustrated in Figs. 14 and 15, except for a modified arrangement of the controlling circuit, may be assumed to be like that illustrated in Figs. 11, 12 and 13, and described in connection with the structure illustrated in Figs. 1 to 8, inclusive. In this arrangement, the electrodes are combined in such a way as to form a single barb which is forced into the bread slice. As illustrated, said modified arrangement of electrodes includes a small tapered truncated tubular electrode 61 that is set into an insulating plug 62, which in turn is anchored to the cross bracket 63 rigidly secured to the base 12.

Extended through but insulated from the tubular electrode 61 is a small rod-like stem 64 of an electrode 65. This electrode 65 forms a sharp-pointed continuation of the barb made up of the two electrodes, but is spaced from the electrode 61 by an insulating sleeve 66. The barb formed by the electrodes thus assembled is very small, to wit: about the size shown in Fig. 1', the size thereof being greatly exaggerated in Fig. 15. With this arrangement of electrodes when the bread is drawn down under downward movement of the toast ejector or carrier and the positive pulling action of the toothed gripper arms 40—40', the barb made up of the electrodes will be forced into the bread up into the bread slice approximately in the plane of the medial line thereof and hence both electrodes will be far from the exposed faces of the bread and not directly subject to the cooking heat.

With the arrangements of electrodes shown in Figs. 1 to 13, inclusive, because of the arrangement of electrodes close to the outer faces of the bread slice, the resistance to the flow of current through the bread between the electrodes, will increase from or substantially from the beginning of the toasting action. With the arrangement of electrodes illustrated in Figs. 14 and 15, the action will differ in the following respects. Under the initial toasting or cooking action, the moisture will be driven from the face surfaces of the bread to the interior thereof and hence at the initial part of the toasting action, the resistance to the flow of current through that portion of the bread that bridges the insulated space between the electrodes 61 and 65, will first decrease and thereafter will increase. It will of course be understood that the amount of current flow through controlling circuit including

the electrodes 61 and 65 will be very small as compared with the current flowing through the heating elements, and in fact, will be so small that the heating action produced from the controlling circuit so far as drying or heating action is concerned, will be negligible.

The fact that under some conditions the resistance in the bread being toasted or the article being cooked will, at some time during the cooking operation, decrease with the resulting increase in flow of current in the controlling circuit, makes possible the use of an arrangement wherein the interrupting of the cooking action will be caused to take place when the current flow in the controlling circuit is increased to a predetermined extent, instead of being decreased as in the preferred arrangements illustrated.

Such an arrangement is illustrated diagrammatically in Fig. 16. In this arrangement, Fig. 16, I have used the electrode assembly best shown in detail in Fig. 15. The current is supplied to the heating coils 15 from lead wires 44', in one of which is a manually-operated switch 67 that must be closed when current is to be supplied to the heating coils.

The electrodes 61 and 65 are connected in series with electro-magnet 68 by shunt wires 69—70. A solenoid 71 is connected across the leads 44' by shunt wires 72 and 73, in which wire 73 is interposed a normally open switch 74 that has an armature 75 subject to electro-magnet 68. Solenoid 71, when energized, holds toward the left a core 76 that is connected to a trip dog 77. This trip dog normally holds against rotation a member 78 of a clockwork or timed mechanism 79 of any suitable type, but, as shown, the one that is operated by a spring 80. With this arrangement, Fig. 16, when the resistance in the bread drops say from seven ohms down to four ohms, the flow of current through the high resistance magnet 68 will be increased to such an extent that it will act on armature 75 and close switch 74; and this will close the circuit through solenoid 71, thereupon the resulting movement of the core 76 will cause dog 77 to release elements 78 of the clockwork 79. The reason here for employing the clockwork is to delay the cutting off of the current through electrical heating coils 15. It has been found that in ordinary toasting action, the drop in the resistance due to the driving of moisture from the surface into the interior of the bread, and the resulting of tripping of the clockwork, will take place at too early a period, that is, before the bread has been properly toasted. Assuming that this tripping would take place about fifteen seconds, the clockwork would be arranged to run fifteen seconds before it performed its function of actually tripping or cutting off the supply circuit. The clockwork therefore acts simply as a trip-delaying device. Even with this arrangement, which is somewhat complicated and which may be greatly modified, there is still the advantage that the tripping action would be controlled not by actual time, but by the moisture content at the interior of the toast. Of course, as indicated, the clockwork may be arranged to control the supply circuit or other devices in different ways. For example, the clockwork might operate a tripping crank 81 having connections to the switch 67 or to any other switch in a supply circuit.

Moreover, the clockwork might be utilized to control the supply circuit to the heating elements and the tripping action of the bread to the ejector or carrier in the same or very much the same way.

as illustrated in the Strite Patents Nos. 1,387,670, issued August 16, 1921, and 1,394,450, issued October 18, 1921, both entitled "Bread toasters".

From the foregoing, it is evident that both the apparatus and the process herein disclosed are capable of wide ranges of modification within the scope of the invention herein disclosed and claimed.

This application is filed as a continuation in part of my pending application, Serial No. 504,777, filed December 26, 1930 and entitled "Automatic toaster".

What I claim is:

1. In an apparatus for cooking substances that contain a variable amount of moisture, an electrical heat radiator, a supply circuit therefor, a normally open switch in said supply circuit, a shunt of relatively high resistance connected across said supply circuit and including an electro-magnet and spaced electrodes, said electrodes being arranged to contact with the substance being cooked to thereby include said substance in said shunt circuit, and said electro-magnet when fully energized serving to hold said switch in circuit-closing position, but to automatically permit opening of said switch and supply circuit when the increasing electrical resistance due to decreasing moisture content in the substance has reduced the current flow through said shunt and electro-magnet to a predetermined point.
2. The structure defined in claim 1 in further combination with means for projecting said electrodes into contact with the substance being cooked substantially simultaneously with closing of the circuit through said shunt and its electro-magnet, and for dis-associating said electrodes with the said substances when said electro-magnet is de-energized sufficiently to release and permit opening of the switch in said supply circuit.
3. In an apparatus for cooking substances that contain a variable amount of moisture, an electrical heat radiator, and automatic electro-magnetic means involving a circuit arranged to include, as a part thereof, the substance being cooked, and automatically operative to render said radiator inactive on said substance, when the increasing electrical resistance due to decreasing moisture content in the substance being cooked has reduced the current flow therethrough to a predetermined point, and in which structure the magnetic means includes an electro-magnet in its circuit, and a trip-acting armature arranged to be held and released by said magnet, a normally open switch controlling the supply of current to said electrical heat radiator and arranged to be closed when said armature is held by an electro-magnet and to be opened when said armature is released.
4. In a toaster, the combination with electrical heating elements and a circuit therefor including a normally open switch, of means for closing said switch at will to start the toasting action, of a toast ejector under strain to move in a direction to eject the toast, a latch for holding said toast ejector in retracted position, and means involv-

ing a circuit arranged to include the positioned toast as a part thereof, and operative to open said switch and cut off the current supply to said electrical heating elements, when the increasing electrical resistance due to decreasing moisture content in the toast has reduced the current flow therethrough to a predetermined point.

5. In a toaster, an oven, electrical heating elements in said oven, a toast ejector under strain to move and eject the toast, a latch for securing said ejector against toast-ejecting movement, and means for releasing said latch including a latch tripping armature and a control circuit, said circuit including an electro-magnet and electrodes arranged to engage the toast and cause a portion thereof to form a part of said control circuit, said magnet, when energized to a certain extent serving to hold said armature against latch-releasing movement and said switch closed, but arranged to release the same for latch-releasing and switch-opening actions when the increasing electrical resistance due to decreasing moisture content in the toast has reduced the current flow through said magnet to a predetermined point.

6. The structure defined in claim 5 in further combination with a master lever connected to move with said toast ejector and operative to set the latter in a retracted position subject to said latch, and means operatively connected to said lever operative to engage said electrodes with the toast when said toast ejector is moved to said latch-retained position and disengage said electrodes from the toast when said ejector is released for a toast-ejecting action.

7. The structure defined in claim 5 in further combination with a master lever connected to move with said toast ejector and operative to set the latter in a retracted position subject to said latch, means operatively connected to said lever operative to engage said electrodes with the toast when said toast ejector is moved to said latch-retained position and disengage said electrodes from the toast when said ejector is released for a toast-ejecting action, and gauge devices engageable with the sides of the bread slice and operative to space said electrodes to engage the bread slice at predetermined distances from the exposed surfaces thereof.

8. The structure defined in claim 5 in further combination with a re-setting device rendered operative by extreme movement of said toast ejector to retracted position and operative to move said armature into a switch-closing position subject to the magnet of said control circuit.

9. The structure defined in claim 5 in further combination with a re-setting device rendered operative by extreme movement of said toast ejector to retracted position and operative to move said armature into a switch-closing position subject to the magnet of said control circuit, and a master lever movable with said toast ejector and operative to set the latter in retracted position subject to said latch.

MAURICE H. GRAHAM. 65
